UNITED STATES PATENT OFFICE.

FRANK KUHN, OF DETROIT, MICHIGAN.

ELECTRICALLY-HEATED INSTRUMENT.

1,231,749.

Specification of Letters Patent.

Patented July 3, 1917.

Application filed August 30, 1915. Serial No. 47,928.

To all whom it may concern:

Be it known that I, FRANK KUHN, a citizen of the United States of America, residing at Detroit, in the county of Wayne 5 and State of Michigan, have invented certain new and useful Improvements in Electrically-Heated Instruments, of which the following is a specification, reference being had therein to the accompanying drawings.

10 The invention relates to electrically heated instruments, and has for its primary object increase in efficiency in the distribution of the heat from the resistor to the work surface. To this end the invention comprises 15 the novel means for securing better heat-conducting contact between adjacent members of the instrument, and further for protecting the surfaces from corrosion as hereinafter set forth.

20 In the drawing:

Figure 1 is a sectional elevation illustrating an electrically heated soldering iron to which my improvements are applied;

Fig. 2 is a cross section of Fig. 1; and

25 Fig. 3 is a cross section through the several members of another electrically heated instrument embodying my invention.

In the construction of electrically heated instruments it is usual to employ metals, 30 such as iron, copper, etc., which under the temperature to which the instrument is subjected readily oxidize. As a consequence it is difficult to maintain good heat conducting contact between adjacent members, for the 35 reason that a film of corrosion will be formed therebetween which acts as a heat insulation. Furthermore, the corrosion of contacting surfaces often causes them to adhere to each other so as to render separation difficult, and 40 this is particularly objectionable in instruments which are provided with removable tools.

With the present invention these difficulties have been overcome by rendering the 45 contacting surfaces of adjacent members non-corrodible. As shown in Fig. 1, A is an

electric heater having heat-distributing body B which is recessed for receiving the removable tool C, such as a soldering iron. The body B may be formed of any suitable material such as cast iron, and the electric heat is imparted thereto from a suitable resistor D wound therearound and insulated therefrom. The member C is also formed of any suitable material, such as copper, and the 55 parts are machined to form a close fit so as to secure good heat-conducting contact.

To avoid corrosion and the difficulties resulting therefrom, the members B and C are treated by any suitable process for rendering the contacting surfaces thereof non-corrodible, such surfaces being indicated by heavy lines. Preferably this treatment is one which coats the surface with a non-corrodible metal, such as aluminum, without 65 impairing its heat conduction. Thus the heat which is developed in the resistor D and is transmitted therefrom to the member B is readily transferred to the member C through the contacting surfaces. Also this 70 is accomplished without any corrosion of the surfaces so that any time these members may be separated.

In Fig. 3 is shown a modified construction in which E is an armored electrical 75 heating unit, and F and G members for contacting the opposite sides of said unit. The contacting surfaces of all of these members are treated to be rendered non-corrodible, and therefore when they are clamped together 80 the heat conduction is more perfect.

What I claim as my invention is:—

In an electrically heated instrument, adjacent members in heat-conducting contact, the contacting surfaces of said members being 85 coated with aluminum.

In testimony whereof I affix my signature in presence of two witnesses.

FRANK KUHN.
